UNITED STATES PATENT OFFICE

149,834

DESIGN FOR A BOTTLE CLOSURE

Layton E. Perkins, Milwaukee, Wis.

Application May 3, 1946, Serial No. 129,238

Term of patent 3½ years

(Cl. D58—26)

To all whom it may concern:

Be it known that I, Layton E. Perkins, a citizen of the United States, residing at Milwaukee, in the county of Milwaukee and State of Wisconsin, have invented a new, original, and ornamental Design for a Bottle Closure, of which the following is a specification, reference being had to the accompanying drawing, forming part thereof.

In the drawing:

Fig. 1 is a side elevational view of a bottle closure showing my new design;

Fig. 2 is a top view thereof; and

Fig. 3 is a bottom view.

I claim:

The ornamental design for a bottle closure, substantially as shown.

LAYTON E. PERKINS.
